(57) **CLAIM**

The ornamental design for a navigation system, as shown and described.

DESCRIPTION

FIG. 1 is a front elevational view of a preferred embodiment of the navigation system constructed according to my new design;

FIG. 2 is a top plan view thereof;

FIG. 3 is a right side elevational view thereof, the left side elevational view being a mirror image thereof;

FIG. 4 is a rear elevational view thereof;

FIG. 5 is a bottom plan view thereof, the portions in dash lines being shown for environmental purposes only and forming no part of my claimed design of this embodiment;

FIG. 6 is a front elevational view of an alternative embodiment of my new design, the portions in dash lines being shown for environmental purposes only and forming no part of my claimed design of this embodiment;

FIG. 7 is a top plan view thereof;

FIG. 8 is a right side elevational view thereof, the left side elevational view being a mirror image thereof;

FIG. 9 is a rear elevational view thereof;

FIG. 10 is a bottom view thereof, the portions in dash lines being shown for environmental purposes only and forming no part of my claimed design of this embodiment;

FIG. 11 is a front elevational view of still another alternative embodiment of my new design;

FIG. 12 is a top plan view thereof;

FIG. 13 is a right side elevational view thereof, the left side elevational view being a mirror image thereof;

FIG. 14 is a rear elevational view thereof; and,

FIG. 15 is a bottom plan view thereof.
